UNITED STATES PATENT OFFICE.

BAINBRIDGE W. BURDICK, OF ALBANY, NEW YORK.

DESIGN FOR A GRATE-HOOK SHELL.

SPECIFICATION forming part of Design No. 31,903, dated November 28, 1899.

Application filed October 25, 1899. Serial No. 734,785. Term of patent 14 years.

To all whom it may concern:

Be it known that I, BAINBRIDGE W. BURDICK, a citizen of the United States, residing at Albany, in the county of Albany and State 5 of New York, have invented and produced a new and original Design for Grate-Hook Shells, of which the following is a specification, reference being had to the accompanying drawings, forming part thereof.

10 Figure 1 is a perspective view of a grate-hook shell, showing my new design viewed from its hook end. Fig. 2 is a sectional elevation of the same, and Fig. 3 is a section taken at line 1 in Fig. 2.

15 As shown in the drawings, the leading or material feature of my design consists of a shell having the shape or configuration shown when viewed in perspective and from above its hook end and in the several figures. In

20 this shape or configuration of the shell A the front wall A' of the shell is made in its upper portion a with a straight line, which terminates in the concave portion a' and then runs forward and terminates with the downcurved

25 or convex portion a^2 , which forms the nose end of the hook and terminates at the lower

end wall B of the shell. The rear side of the rear wall C is made with a convex form c from its upper end c' to its lower end c^2 , where it terminates at the lower end wall B, and the 30 lateral side walls D D are shown to be inclining toward each other by being on gradually-tapering lines as they are extended from their upper ends d downwardly to the lower end wall B, as illustrated in Fig. 3, which latter 35 wall B is shown to be run in a straight line from the lower end c^2 of the convex rear side wall C to the convex portion a^2 of the front wall A', and also run in straight line from one lateral side wall to the other. The upper end 40 of this shell A is shown to be open to the interior of chamber e, as shown in the several figures.

Having described my invention, what I claim as new, and desire to secure by Letters 45 Patent, is—

The design for a grate-hook shell as herein shown and described.

BAINBRIDGE W. BURDICK.
